PRINTING MACHINE

Walter T. Gollwitzer, Chicago, Ill., assignor to
 Addressograph Company, Chicago, Ill., a corporation of Delaware

Application November 22, 1930, Serial No. 497,438

46 Claims. (Cl. 101—58)

This invention relates to printing machines of the type wherein variable printing devices are sequentially passed through the machine and it is particularly directed to a selector mechanism for controlling the printing operations of the machine in order that only determined or selected of the printing devices will be used in printing operations.

Printing devices of the character used in the machine of the foregoing type are arranged in a predetermined sequence and when not in use are filed in the drawers of suitable cabinets. The machine embodies a magazine into which the devices in any one of the storage drawers may be introduced and also embodies a mechanism for successively withdrawing the devices from the magazine to pass them through selecting and printing positions in a step-by-step manner to a packer mechanism that directs the devices into a galley wherein they are collected in the same sequence as that in which they were arranged in the drawer when introduced into the magazine. The salient object of the invention is to determine which of the printing devices so passed through the machine are to be used in printing operations.

The embodiment of the invention disclosed herein is one which may be used in the printing of tax bills and the like, but it is to be understood that the disclosure for such purpose is merely exemplary and is not to be interpreted as the only manner in which the invention may be utilized. Printing devices used in the printing of tax bills are often arranged in groups, this being necessitated by the length of the legal descriptions of the parcels of real property to be taxed, for sometimes all of the legal description cannot be conveniently arranged on a single printing device and in such instances legal description is arranged on as many printing devices as is necessary. The first of such a group of printing devices has thereon the name and address of the party being taxed and other pertinent information and all or a part of the legal description, and these are known as lead printing devices. The subsequent or follower printing devices of the group do not have the name and address thereon but have only as much of the legal description as can be conveniently arranged thereon. When the device is used in the printing of tax bills it is sometimes desirable that only certain of the printing devices or groups of printing devices be used in printing operations, as for example, certain persons will pay their taxes annually while others will pay their taxes semi-annually and manifestly when the printing devices are being used to print tax

bills for the second of the semi-annual payments it will be desirable that the printing devices for those parcels of property for which taxes have been paid for the current year not be used in the printing operation. It is therefore another object of this invention to provide a selector wherein not only single successive sequentially arranged printing devices may be selected for printing operations but also to provide a selector wherein printing devices arranged in groups may be selected so that not only one but all of the printing devices of a group may be used or not be used in a printing operation.

The legal description of the parcels of property are so worded that an entire parcel is described thereby, but under certain circumstances such a parcel of property may be divided, that is, a portion or portions thereof may be sold or otherwise disposed of and when this is done, it is desirable that the legal description be changed so that each portion will have an independent legal description. This, of course, necessitates changing the legal description on the printing devices, and it is common to make these changes at the time the property is divided, and therefore new printing devices will be introduced into the sequentially arranged groups of printing devices which will change the sequence, and it is necessary that the newly inserted printing devices not be used in a printing operation until a new sequence, including them, is established. It is therefore a further object of this invention to provide a selector which will determine such newly added printing devices in order that printing operations will not be performed therefrom by the machine.

Further objects are to provide a variable selector that will regulate the printing operations from variable members on the printing devices; to provide a selector wherein a variation of the determined operation or a special operation may be brought about easily; to provide a selector that will normally regulate operation of the printing means of the machine and which will maintain the timed relation of the various elements of the machine; to provide a selector wherein the arrangement of the detecting portion may be varied expeditiously; and to provide a selector mechanism which may be manually positioned to permit repetitious operation of the machine.

In the selected embodiment of the invention shown in the accompanying drawings

Fig. 10 is a detail view showing the interconnection of the parts of the speed changing device; and

Fig. 11 is a fragmentary plan view of one end of the machine with which my invention is illustrated.

For the purpose of describing my invention I have shown a printing machine which embodies a main frame 26 having at the upper end thereof a bed 27 on which the printing operations are performed. A bracket 28 on the main frame provides a bearing 29 in which a shaft 32 is journaled and rotatably mounted on this shaft is a flywheel 30. Power is transmitted to the flywheel from a suitable source by a belt arranged in the groove 31 in the flywheel, or in any other approved manner. A clutch structure 33 interconnects the flywheel and shaft 32. Mounted on the shaft 32 is another clutch structure 34, described more fully hereinafter, which connects the spur gear 35 to the shaft 32. The spur gear 35 meshes with a spur gear 36 rotatably mounted on the shaft 37 and joined to a spur gear 39 by a collar 38. The spur gear 39 meshes with the pinion 40 fixed on the shaft 41 (Fig. 11) extended to the front of the machine into a gear housing 42.

Fixed on the shaft 41 in the gear housing are three gears 43, 44 and 45 (Fig. 8) of progressively greater diameter. Another shaft 63' extends into the gear housing through a bushing 59 and carried by this shaft are gears 46, 47 and 48 meshed with the gears 43, 44 and 45, respectively. The gears 46, 47 and 48 are rotatably mounted on a bushing 49 on the shaft 63'. In the bearing portions of the gears 46, 47 and 48, resting on the bushing 49, are pockets 46', 47' and 48' and in the bushing is an opening 51, and by properly positioning the gears the pockets and opening may be arranged in intercommunication. In the opening 51 is a tumbler 52 (Fig. 9) in the nature of a pin having relieved sections defining rounded portions 53, 54 and 55, axially spaced from each other and circumferentially disposed, each comprising one-third of the diameter of the tumbler. On the outer end of the tumbler is a knob 56 having an opening 57 therein, and the outer end of which is closed, in any desired manner, to confine a spring 58 in the opening. The spring acts on a ball 59 to force it toward the disc 60. The disc 60 cooperates with a flange 49' on the bushing 49 and the gears 46, 47 and 48 are confined

between the disc 60 and the flange 49'. The disc is connected to the shaft 63' by a plate 61, which has an elongated opening therein receiving a similarly shaped portion on the shaft, the plate being connected to the disc by bolts 62. On the face of the knob 56 is suitable indicia which is respectively aligned with the rounded portions 53, 54 and 55. In the face of the disc 60 are three sockets in which the ball 59 may be selectively seated. By turning the knob to move a portion of the indicia thereon into vertical position a certain one of the rounded portions on the tumbler will project beyond the opening 51 and will seat in one of the pockets, depending upon which of the rounded portions is in the described projected position, the ball 59 seating in a socket to retain the parts in this position. In the present instance the portion 54 is disposed in the pocket 47' and therefore the gear 47 is connected to the shaft 63', and in this manner a selected one of the gears 46, 47 or 48 may be connected to said shaft 63'. The ratio between the gears 45 and 48 is 1 to 1; the ratio between the gears 44 and 47 is 2 to 1; and the ratio between the gears 43 and 46 is 3 to 1. Therefore, the shaft 41 may be either arranged to rotate at the same speed as the shaft 63', or it may be arranged to rotate either twice or three times as rapidly depending upon which of the gears is connected to the shaft 63'.

A shaft 63 is journaled in a bearing 64 (Fig. 11) and in a bearing 65 adjacent the compound gear train 68. The end of the shaft 63' extending from the end of the housing 42 is journaled in a bearing 66 adjacent the compound gear train, which serves to reduce the speed of the shaft 63 so that this shaft will rotate in determined relation to the rotation of the shaft 32. On the shaft 63 is a bevel gear 69 which meshes with a bevel gear 70 on the cam shaft 71 which extends longitudinally of the machine and which is journaled in a suitable manner.

On the inner end of the shaft 32 is a bevel gear 72 meshed with a bevel gear 73 on the platen operating shaft 74. When the clutch 33 connects the flywheel 30 to the shaft 32, this shaft and consequently the shaft 74 is rotated, but the other shafts, above described, are not rotated until the clutch 34 is engaged. The utility of this arrangement is set forth hereinafter.

The machine includes as a part of the printing means thereof a platen P, and this platen is operated by means on the platen operating shaft 74 and is carried by the platen arm 77. The platen arm 77 includes a leg 76 (Fig. 4) pivotally mounted on a lug 75 on the bed 27. Branch arms 78 and 79 are provided on the platen arm and are extended on opposite sides of the shaft 74, and rotatably mounted thereon are rollers 80 and 81 respectively engaging conjugated cams 82 and 83 fixed on a sleeve 100 disposed about the shaft 74. Extending forwardly from the arm 77 is the platen or stamper arm 84 which carries the platen P, and as the sleeve 100 rotates with the shaft 74 the rises on the cams 82 and 83 impart a rocking movement to the platen arm about the pivotal mounting thereof on the lug 75 to move the platen toward and away from printing position to perform the printing operation.

The selector forming the subject matter of this invention controls the reciprocation of the platen and the printing device feed in a manner to be set forth. In my co-pending application, Serial No. 497,439, filed in the United States Patent Office on November 22, 1930 the manner in which

a sheet, such as a tax bill, is moved into the printing position to be operated on by the platen P is fully described. In my co-pending application, Serial No. 497,440, filed in the United States 5 Patent Office on November 22, 1930 I described the manner in which the sheets are stored and supplied to the sheet positioning mechanism. Herein, the selector is disclosed as it is used to control the printing operations on sheets supplied and moved in the manner described in these co-pending applications, but it is to be understood that this is merely illustrative and therefore this disclosure is not to be taken as a limitation of the invention to such use, for the selector 10 is capable of being used in many other ways.

Fixed on the platen operating shaft 14 is an eccentric 12 (Fig. 3), surrounded by a band 13 embodying a portion 14 carrying a plunger 15 on which a collar 16 is secured by the pin 17. 15 The plunger 15 is extended through a sleeve 18 carried by an arm on the printing device feed rocker 19 that is pivotally mounted at 20 on the bed 27. The printing device feed rocker includes an arm 21 (Fig. 5) having a pawl 22 pivotally 20 mounted at the outer end thereof including a recessed nose portion 23 successively engageable with the pins 24 on the sprocket 25 mounted on the bed 27 and about which the printing device feeding chain 85 is directed. On this chain are 25 pawls 85 or other suitable devices of the character well understood in the art, which engage the edges of the printing devices to sequentially move these devices through the printing device guideway 86 in one direction.

30 A latch 87 having a shoulder 88 thereon normally engaging the collar 16 is pivotally mounted at 89. When the printing device feed rocker is to be operated the shoulder 88 on the latch 87 is engaged with the upper edge of the collar 16 (Figs. 3, 6 and 7) by the action of the spring 87' and the rotative movement imparted to the eccentric 12 is translated to reciprocate the plunger 15. As the plunger and printing device feed rocker will be interconnected a rocking movement will be imparted to the rocker and the pawl 22 thereon will successively engage the pins 24 to impart a step-by-step movement to the sprocket 25 to thereby bring about a step-by-step advancement of the printing devices 35 through the guideway 86.

40 The detecting portions of the selecting mechanism of my improved device are operated from the printing device feed rocker 19. The detecting portions include the casting 90 pivotally mounted on the bed 27 at 91 and having a bar 92 (Fig. 5) fixed thereto engageable by the roller 93 on the rocker 19. When the rocker 19 is motivated in the manner previously set forth the roller 93 is engaged the bar 92 and pivots the casting 90 about the pivotal mounting 91 thereof. As best 45 shown in Fig. 6, the selector bar 94 is pivotally mounted at 95 on the casting 90 and includes an arm 91' normally urged into engagement with the pin 92' by the spring 93' extended between a spring anchor on the bar 94 and a spring anchor 96 depending from the casting 90. In the 50 selector bar 94 a plurality of openings 97 are provided in which the headed pins 98 are inserted, the heads of said pins resting on the upper surface of the bar 94 and being held in engagement therewith by a plate 99 (Fig. 1) having slots 101 and 102 therein, the slot 102 being passed about the rivet 103 fixed in the bar 94 in such a manner that one end of the plate 99 is secured below 55 the head of the rivet, and a screw 104 is passed

through the slot 101 into the bar 94 and by tightening or loosening this screw the plate 99 may be secured or detached, and when detached it may be removed and therefore the pins 98 may be positioned or removed from the openings 97 to determine the selection. 5

When the roller 93 engages the bar 92 and moves the casting 90, the selector bar 94 is moved toward the printing device D in selecting position, indicated by 105, the printing device D in 10 printing position being indicated by 106. The printing device 106 in printing position and the printing device 105 in selecting position are positioned side by side, the printing device 106 being 15 the first in the order of passage through the machine. On each of the printing devices are members T (Fig. 7), in the form of detachable tabs in the disclosure, and the printing devices, as is well understood in the art, have retention means thereon for attaching tabs thereto. The 20 tabs may be disposed at different positions along the edge of the device, this edge being disposed rearwardly as the printing devices pass through the guideway 86, it being understood that the printing devices are introduced into a magazine 25 M in a predetermined sequential order and that the printing device feed arrangement successively withdraws printing devices from the magazine and passes them through the guideway first into selecting position and then into printing 30 position, after which the devices are passed to a suitable packer mechanism which introduces the devices into a galley G (Fig. 2) wherein they are collected and stored in the same sequential order as that in which they were arranged when 35 introduced into the magazine M.

40 A selector mechanism is often so arranged so that printing operations will be performed on printing devices having the tabs located in predetermined positions, these positions being determined by the positions of the pins 98 in the openings 97, the location of the openings 97 corresponding to the positions of the retention means on the printing devices. The selector mechanism may also be arranged to render the platen inoperative 45 when the detecting portions of the selector engage tabs located in predetermined positions, and when the device is arranged in this manner it is said to be in skip position while, when it is arranged in the first described manner, it is 50 said to be arranged in print position.

Should the casting 90 be moved in the manner described the selector bar 94 will also move, and in the event the tabs on the printing device 105 are not positioned similarly to the location of the pins 98 the selector bar 94 and the casting 90 will move as a unit to the limit of the movement in the direction in which the casting 90 is moved by the action of the roller 93. However, should the tabs T be positioned similar to the 60 location of the pins 98 the movement of the selector bar with the casting will be interrupted and therefore this bar will be pivoted, about its mounting 95, relative to the casting 90. Connected to the selector bar 94 is an arm 107 (Fig. 65 7) having the lower end of a link 108 pivotally connected thereto at 109. When the selector bar 94 moves with the casting 90 the centers of the pivotal mountings 91 and 109 are coincident, but when the selector bar 94 is stopped by engagement of the pins with tabs the coincidence of these centers is altered and the link 108 is 70 moved downwardly.

75 The selector mechanism includes a bracket 110 depending from the housing 111 surrounding the 75

- platens operating and the selector mechanisms. A bell crank 112 is pivotally mounted at 113 on the bracket 110 and eccentrically journaled in the outer end of the arm 114 of the bell crank 5 112 is a pin 115 having a knob 116 secured thereto. The upper end of the link 108 is connected to the eccentric pin 115. The eccentric pin is so mounted that it may be disposed in two opposite positions and these two positions are indicated 10 by indicia on the knob 116 which, in the present instance, consists of the letters P and S, indicative of print and skip operations as brought about by the selector mechanism. In the present instance the knob 116 is so positioned that the letter S is in upper position and the selector mechanism is arranged to effect skip operation.
- It has been pointed out that until the bar 94 is stopped, the pivotal mountings 91 and 109 have their centers coincident and therefore the 20 position of the link 108 is fixed. Thus, when the eccentric pin 115 is turned the bell crank 112 will be moved by reason of the mounting of the pin in the arm 114 thereof and the fixed position of the link 108. On the arm 117 of the bell 25 crank 112 is a head 118 having notches 119 and 120 therein providing a nose 121 therebetween, the head 118 having shoulders 122 and 123 thereon at the outer ends of the notches 119 and 120, respectively.
- 30 When the parts are located by the depicted disposition of the pin 115 the bell crank 112 is positioned as shown in Fig. 6 and the dog 124 is disposed in the notch 119. The dog 124 is carried by the yieldable arm 125 fixed to the rocker 126 pivotally mounted on the bracket 110 at 127. Pivotally mounted at 128 on the bracket 110 is a rocker 129 including arms 130 and 131. At the outer end of the arm 131 a rod 132 is pivotally connected that extends through a bore in the boss 133 on the sleeve 18. A collar 134 is adjustably mounted on the rod 132 and is held against the upper face of the boss 133 by the spring 135 extended between spring anchors on the rocker 129 and the bracket 110.
- 45 When the rocker 19 moves upwardly the rod 132 is moved upwardly and the arm 131 of the rocker 129 also moves upwardly. On the rocker 129 is an arm 136 having a plate 137 secured thereto including a nose 138. In the rocker 126 50 there is a recess 138 providing a nose 139.
- As has been described, at the time the casting 90 moves the selector bar 94 toward the printing device 105, the coincidence of the centers of the 55 mountings 91 and 109 is altered, if the tabs on the printing device 105 engage pins 98 and interrupt movement of the selector bar 94, and this moves the link 108 downwardly. When the link 108 so moves the arm 117 of the bell crank 112 the dog 124 is unseated from the notch 119 and the nose 60 thereof seats on the nose 121. When the rocker 19 was moved upwardly the rocker 129 was motivated, as described, and therefore the arm 136 moved into a position substantially similar to that shown in Fig. 7. The parts then assume 65 positions such that the plate 137' extends into the recess 138, as shown in Fig. 7, and the shoulder 137 may then engage the shoulder 139 to lock the parts in position. At the time the arm 131 moved upwardly the arm 130 of the rocker 129 70 moved downwardly and at this time the pawl 140 pivotally mounted at 141 on the disc 142 fixed on the shaft 74 was in a position slightly forward of that illustrated in Fig. 7. When the shoulders 137 and 139 are engaged in the just described 75 manner the arm 130 will be retained in this posi-

tion and the end thereof will engage the end of the pawl 140 and will pivot the same against the action of the spring 143 and thus the nose of the pawl will disengage the shoulder 144 on the sleeve 100.

When the nose of the pawl 140 engages the lug 144, the sleeve 100 is driven with the shaft 74. Therefore when the pawl is disengaged from the shoulder the movement of the sleeve 100 will be interrupted and no movement will be imparted to the conjugated cams 82 and 83 and therefore the platen P will not be operated. It is therefore manifest that a printing device with tabs thereon in accordance with the location of the pins 98 will render the platen inoperative when the knob 116 is disposed as shown in Fig. 7 and thus the printing device will be, as it is termed, skipped.

In the foregoing description I have set forth the operation of the device when it is arranged to skip a printing device having tabs thereon in predetermined positions. However it is often desirable to print such printing devices rather than skip them and when this is desired the knob 116 is turned to position the letter P in upright position. Thus, when the centers 91 and 109 are coincident the bell crank 112 will be so positioned that the nose of the dog 124 will be disposed on the shoulder 122. Thus, when the casting 90 is moved in the manner described and movement of the selector bar therewith is interrupted by the engagement of the pins 98 with tabs T on the printing device 105 the center of the pivotal mounting 109 is moved from coincidence with the center 91 and the bell crank 112 is so moved that the dog 124 seats in the notch 119 and thus the rocker 126 is positioned substantially as shown in Fig. 6. Therefore, when the rocker 129 is moved the plate carrying the portion 137 will not be positioned in the recess 138 and therefore the rocker 129 will not be locked in its lower position and thus the end of the arm 130 will not be in the path of movement of the pawl 140 and the inter-connection of the shaft 74 and the sleeve 100 through the disc 142, pawl 140, and shoulder 144 will not be interrupted and therefore the conjugated cams 82 and 83 will be operated to bring about a printing operation of the platen. However, when the tabs T on the printing device 105 are not in the predetermined positions the coincidence of the centers of the pivotal mountings 91 and 109 is not altered and because the nose of the dog 124 is resting on the shoulder 122 the rocker 126 remains positioned in its upper position, and therefore when the rocker 129 is moved, the plate 137' enters the recess 138 and the shoulders 137 and 139 are engaged and thus the parts are locked in position so that the interconnection of the shaft 74 and the sleeve 100 is interrupted and therefore printing devices not tabbed in the predetermined manner will be skipped.

It has been pointed out that the printing device 105 is in selecting position and that the printing device 106 is in printing position. Moreover, it is apparent that the operation of the platen is determined from the printing device 105. Therefore, immediately following the determination of the selection the rocker 19 will be moved to impart a driving movement to the sprocket 25 and the chain 85 will therefore be motivated and the printing device 105 will be moved into the position of the printing device 106 and it is from the printing device 106 that the impression is made by the platen P.

In my co-pending application, Serial No. 75

497,439, filed in the United States Patent Office on November 22, 1930, I have described how a tax bill or other sheet to be printed is moved into printing position, and therein it is set forth that such bills often have more than one section and that impressions are made from each printing device on each section of the bill, when the selector determines that the printing device is to be used in a printing operation. Moreover, in the last referred to application I have described how the machine is arranged to determine whether one, two or three impressions are to be made on the bill, and as pointed out therein this is related to the relative rotation of the cam shaft 71 with respect to the rotation of the platen operating shaft 74. If, for example, a two-section tax bill is to be printed two impressions will be made from the printing device in printing position and under such conditions the cam shaft 71 makes one revolution to two of the platen operating shaft. When two or more impressions are to be made from each printing device the selecting and the printing device feeding means are rendered inoperative on all save the last printing operation, and to accomplish this the following mechanisms are provided:

On the cam shaft 71 is a cam 145 (Fig. 6) engaged by a roller 146 on the arm 147 of the rocker 148 pivotally mounted at 149 on the lug 150 carried by the bed 27. The rocker 148 includes an arm 151 having a cam surface 152 thereon. On the latch 87 there is a pin 153 and when the rise on the cam 145 engages the roller 146, the arm 147 of the rocker 148 is pivoted downwardly which pivots the arm 151 of said rocker upwardly, and the cam surface 152 thereon engages the pin 153 and disengages the shoulder 88 from the collar 16 by pivoting the latch 87 about the pivotal mounting thereof. Therefore, during the operation of the shaft 74 on all but the last of the printing operations the plunger 15 will move without imparting any movement to the rocker 149. However, during the time the last impressions are being made from the printing device 106 the rise on the cam 145 will disengage the roller 146 and therefore the cam surface 152 will move from engagement with the pin 153 and the shoulder 88 will again engage the collar 16 and therefore the rocker 149 and consequently the detecting portions 50 of the selector mechanism will be rendered operative, and thus a selection will be made from the printing device 105. Further, the printing device feed will be rendered operative.

It has been pointed out, however, that in the printing of tax bills and the like the printing devices are often arranged in groups consisting of lead and follower devices. In the disclosed arrangement the selection is made from the lead printing devices, not from follower printing devices, and it is therefore manifest that if the selector be rendered operative immediately after impressions have been made from a lead printing device the selector mechanisms would operate on follower printing devices if there are any. This, however, is avoided by providing the following arrangement:

The follower printing devices will have a tab T' (Fig. 5) or other identifying means positioned thereon in a certain definite location to engage a pin 154 and cause engagement of the contacts 155 and 156 to close an electric circuit to the solenoid 157 at a determined time in the operation of the machine regulated by the switch 195 (Fig. 1) including an operating lever 196 operable by a pin 197 on the disc 198 mounted on the

cam shaft 71. Current will be supplied from the line wires 199 and 200, (Fig. 5a) connected to conductors 201 and 202 by the switch 203, the conductors 201 and 202 being directed to a motor 204 which is the source of power heretofore referred to. Conductors 205 and 206 are respectively connected to the conductors 201 and 202, and to conductors 207 and 208 by the switch 209. When the switch 203 is open, operation of the machine is prevented and opening of the switch 209 prevents operation of the electrical portions of the selector. Thus, when both the switches 203 and 209 are closed and the contacts 155 and 156 and the switch 195 is closed, the solenoid 157 will be energized in the following manner: Current will flow from the conductor 199 to the conductor 201, through conductor 205, conductor 207, contact 155, contact 156, conductor 210, winding of the solenoid 157, conductor 211, switch 195, conductor 212, conductor 208, conductor 206, conductor 202, to conductor 200. The solenoid 157 includes an armature 158 extended through an opening 160 (Fig. 6) in the bracket 110 and includes a pointed end 159. On the rocker 126 there is an T-shaped plate 161 embodying an upwardly extending portion having a knife edge 162 thereon. It has been described how the rocker 126 is disposed in a certain position by the selector and once the rocker has been set it is held in the determined position until another selection is performed. The knife edge 162 is aligned with and arranged adjacent to the opening 160 and when the rocker is positioned this knife edge is disposed on one side or the other of the center of the opening 160. Therefore, when the solenoid 157 is energized the armature 158 moves to dispose the pointed end 159 thereof in the path of the knife edge 162, and therefore the rocker 126 will be retained in position by the engagement of these edges. Thus, when the follower devices move into selecting position after a lead device has been in this position and determined the setting of the rocker 126, said rocker will be held in this position until another lead device moves into selecting position, for each follower device will be equipped with a tab T' that will bring about the closing of the contacts 155 and 156, but no such tab is provided on the lead devices.

In the foregoing description I have pointed out that the operation of the shaft 74 and the cam shaft 71 should be in timed relation but this might be more accurately stated in that it is the operation of the sleeve 100 and the shaft 71 which is in timed relation as the shaft 74 rotates constantly when the machine is operated. I have set forth that the sleeve 100 is disconnected from the shaft 74 when no printing operation is to be performed by the platen and when this occurs it is necessary that operation of the cam shaft be interrupted so that the timed relation may be maintained. Moreover, it has been described that the disconnecting of the sleeve from the shaft is brought about by positioning the arm 130 of the rocker 129 in a determined position. I have therefore provided an arrangement operable from the rocker 129 for interrupting movement of the cam shaft 71 when a printing device is to be skipped and this includes the following devices: Connected to the rocker 129 is a bar 166 (Fig. 2) which has a depending lug 167 at one end thereof on which there is a roller 168. Suitably supported on the bracket 28 is a rocker 169 carrying a roller 170 engageable by the roller 168. When the roller 168 engages the

roller 170 the tongue 171 (Fig. 2) carried by the rocker 169 is moved into the path of the pawl 172, the nose of which normally rests in the pocket 173 on the collar 174 fixed on the shaft 32. 5 The pawl 172 is carried by the gear 35 of the clutch 34. Therefore, when, in the rotation of the clutch structure with the shaft 32, the end of the pawl 172 engages the end of the tongue 171, after the same has been positioned as above described, the nose of the pawl is retracted from the pocket 173 and thus the plate 173 is disconnected from the shaft 32 and therefore rotation of the gear 35 is interrupted. It has been previously described how the gear 35 meshes with 10 the gear 36 and how other devices, including the speed changing mechanism, previously described, are operable from the gear 35 to bring about operation of the cam shaft 71. Therefore, movement of the cam shaft will be interrupted when 15 the pawl 172 is disconnected as described.

In my co-pending application, Serial No. 497,439, filed in the United States Patent Office on November 22, 1930, and in my co-pending application, Serial No. 497,440, filed in the United 20 States Patent Office on November 22, 1930, I have described how the sheet feeding means 175 is operated from a shaft 176 by the pinion 49 through an intermediate gear 177 which meshes with a gear 178 fixed on the shaft 176. On the shaft 30 176 there is a disc 179 (Fig. 1a) engageable by brake shoes 180 and 181 and these brake shoes are engaged with the disc by a lever 182 pivotally mounted at 183 and operable by the electrical relay 184 in the following manner:

35 On the shaft 32 there is a cam 185 (Fig. 2) and fixed on the housing of the clutch 34 is a switch 186 having a plunger 187 that is engaged by the rise on the cam 185 during each revolution of the shaft 32 whereby the switch is closed upon 40 each revolution. A circuit, however, is not closed by the switch 186 unless the contacts 163 and 164 (Fig. 6) have been engaged, this being brought about by the adjustable member 165 on the arm 131 of the rocker 129. The contacts 163 and 164 will be engaged only when the arm 131 is in the uppermost position (Fig. 7), for the arm is so located when rotation of the cam shaft 71 45 is interrupted, for it is such positioning of the arm that causes interruption of the cam movement. Therefore, if the switches 203 and 209 are closed the relay 184 will be energized in the following manner:

50 Current will flow from the line wire 199 through conductor 201, conductor 205, conductor 207, conductor 213, contact 163, contact 164, conductor 214, through the winding of the relay 184, conductor 215, switch 186, conductor 216, conductor 208, conductor 206, conductor 202, to line wire 200. When the relay 184 is so energized the armature 188 thereof is attracted and as this armature is connected to the lever 182 said lever will be moved to momentarily engage the brake shoes with the disc and thus arrest rotation of the shaft 176. Thus, rotation of the cam shaft 71 is instantly arrested when the arm 131 is in its uppermost position and the arm 130 will therefore cause disengagement of the pawl 140 from the shoulder 144. Moreover, movement of the sleeve 169 is also arrested and it is manifest that the timed relation will be maintained, for the mechanisms are so constructed that the clutch 34 will be reengaged at a time in the cycle of operation relative to the time at which the pawl 140 reengages the shoulder 144. The sheet feed-

ing device 175 is also stopped along with the cam shaft 71.

It is sometimes desirable that a certain group of printing devices be printed and often this group is tabbed in a manner substantially similar 5 to another group with the exception that an additional tab will be provided on the devices of one group that is not provided on the other group or a switch tab may be provided that can be set in different positions to divide the printing devices into groups. To segregate such a group of printing devices a pin of greater length than the pins 98 heretofore described will be arranged in a position to correspond with the position of the tab defining the group. Therefore, if the selector 10 is set to print devices tabbed in a certain manner the bell crank 112 will be positioned to dispose the nose of the dog 124 on the shoulder 122 and when ordinary length pins bring about the operation the dog seats in the notch 119, but when the 15 longer pin brings about the operation the bell crank 112 will be moved in an amount greater than it is ordinarily moved and therefore instead of the dog 124 seating in the notch 119 the nose thereof will engage the nose 122 and thus operation 20 opposite to that ordinarily brought about will occur. When the mechanism is set in skip position the dog 124 is normally disposed in the notch 119 and moves onto the projection 121 when a printing device is to be skipped as is determined by ordinary length pins. But, when a longer pin engages a tab the dog 124 will move out of the notch 119 but instead of seating on the nose 121 it will seat in the notch 120, and here again operation opposite to that brought about 25 by the ordinary length pins will occur.

It is often desirable to operate the machine repetitiously as during testing of the machine or at other times and this is accomplished in the following manner: Extending downwardly from 40 the housing 111 is a rod 189 connected at 190 to the arm 151 and having a knob 191 slidably connected thereto at the upper end thereof. On the knob 191 is a pin 192. The knob 191 is rotatable also on the rod 189 and when raised and turned 45 into one position it may be aligned with the restricted opening 193 in the housing 111 and when in this position the rod 189 is held in an upper position to so locate the cam surface 152 that the pin 153 will be engaged thereby for the purpose 50 described heretofore, but when the knob is rotated to align the pin with the enlarged opening 194 the rod 189 is lowered and the arm 151 may operate in an unhampered manner because of the slidable connection between the rod 189 and the knob 191. 55

The operation of the device is as follows: The printing devices are introduced into the magazine and are withdrawn therefrom and are sequentially passed through the guideway 86 first through selecting and then into printing position after 60 which the devices are discharged into a suitable galley. If the printing device which moves into selecting position is tabbed in accordance with the group it is desired to print, and the knob 116 is set with the indicia P in upper most position, 65 the operation will be as follows: At the start of a cycle of operation the dog 124 will rest on the periphery of the arm 117 at the point 122. If the machine is put into operation without feeding printing devices or without any printing devices 70 passing the selector bar and as long as a pin in the selector bar does not contact the tab, no relative motion will be imparted to the arm 117. Consequently, the dog 124 will remain at point 122 thereby holding the rocker 126 in its uppermost 75

position so that the nose 137 on rocker 129 will engage the nose 139 and rocker 129 will be latched in its upper position. It is to be understood that the rocker 129 is turning in a clockwise direction as viewed in Fig. 6 during the time that the selector bar is being depressed by roller 93 on the rocker 19. The pawl 140 has been previously disengaged by the arm 130 so that the sleeve 100 is not turning and also the cam shaft 71 is stationary due to the position of the rocker 129 and cooperating parts. The roller 146 on arm 147 will be resting on the low part of cam 145. It will be noticed from this that when the selector parts are set to cause a printing device to be skipped the roller 146 will rest on the low part of the cam 145 so that the machine will feed printing devices consecutively and will not duplicate until shaft 71 is again turning.

When the printing devices start through the machine the nose 137 will remain seated against shoulder 139 until a pin on the selector bar strikes a tab. During every operation of the arm 19, or when arm 19 reaches the limit of its clockwise rotation, the rod 132 is lifted and the rocker 129 is rotated a sufficient amount so that the nose 137 will be cleared slightly from the nose 139 thereby permitting the free positioning of the pawl 126. On the beginning of the next cycle and when a printing device tabbed to correspond to the desired group is in the selecting position and underneath a regular length pin in the selector bar, the operation is as follows:

The rocker 19 begins to rotate in a clockwise direction depressing the selector bar so that the pin 98 will approach the tab and the rod 132 will be lifted. As the rocker 19 rotates clockwise, as before stated, the selector bar will be depressed and when the pin 98 strikes a tab further motion of the pin is arrested. However, rocker 19 completes its motion. Therefore, the roller 93 (Fig. 5) engaging the bar 92 will always rotate casting 90 to a fixed position and consequently from the time that the pin 98 strikes a tab a relative motion of the selector bar 94 to the casting 90 will be set up and which movement will be in a counter-clockwise direction. This motion will be imparted through link 108 connected to the arm 107 on the selector bar 94 and at the other end to rocker 117 at 115. If the pin 98 striking a tab is of the regular length the motion set up by its striking a tab will be just sufficient to rotate rocker 117 a sufficient amount that notch 119 will position itself under the dog 124. This occurs just at the time that the rocker 19 has completed the limit of its motion in a clockwise direction and the relative position of the parts now is as follows:

The dog 124 will be resting in notch 119 as shown in Fig. 6. Rocker 129 will have reached the limit of its clockwise rotation positioning nose 137 as shown in Fig. 7 to permit free action of pawl 126. As the machine now continues to rotate, the rocker 129 will commence to rotate in a counter-clockwise direction much more rapidly than the lifting of the selector bar. Consequently, dog 124 will rest in its position a sufficient length of time so that blade 137 will travel past shoulder 139 and latching up of arm 129 is prevented and at the end of the cycle the relative positioning of the parts will be as follows: The selector bar will be in its upper position with dog 124 again resting at 122, nose 137 not having latched up permits rocker 129 to rotate the limit of its counter-clockwise rotation lifting arm 130 clear so that pawl 140 which about at this time arrives in the position shown in Fig. 6 permits it to engage

shoulder 144 to pick up the sleeve which operates the stamper arm and also the other mechanism as described.

The foregoing operation is brought about by a lead printing device and if one lead printing device is followed by another and the second device is to be printed as above described, the foregoing operation will be repeated. However, if one or more follower plates are behind the lead printing device the solenoid 157 will be energized in the manner described and will hold the selector mechanism in the setting determined by the lead plate and this setting will be maintained until another lead plate moves into selecting position.

If the indicia S is in upper position whereby printing devices tabbed in a certain way are to be skipped, then the nose 124 will normally be positioned in notch 119 instead of resting at 122 and when the pins in the selector bar engage tabs corresponding to the set-up of the pins, the nose 124 will seat on point 121 thereby causing a latching up of the blade 137 on the shoulder 139 which causes arm 130 to engage pawl 140 whereby the pawl will disengage the shoulder 144 and the platen arm will not be operated and hence the printing device will be fed through the machine without an impression being taken therefrom. When this occurs, rotation of the cam shaft 71 is also arrested and this cam shaft will not again be rotated until the nose 138 has been released from the nose 139 and when movement of the cam shaft is arrested the cam 145 will be in the position illustrated in Fig. 6 whereby the printing device moving means will continue to operate and this operation will continue until a printing device not tabbed in the determined manner moves to selecting position whereupon the nose 124 will remain in the notch 119 and hence the pawl 140 will not be disengaged from the shoulder 144 and the platen will operate as described.

In the foregoing description I have set forth how my improved selector is used in connection with the printing of tax bills and it has been shown that by merely turning the knob 116 the selector will control operation of the machine so that printing devices having tabs therein in certain predetermined positions may be printed or skipped. Moreover, I have described how the selector operates to stop portions of the machine, which are independent of each other in certain respects but which have the operation thereof timed, and I have shown how this selector may be used to interrupt operation of such parts without altering the timed relation thereof. Furthermore, the selector described herein is one which will operate either successively on printing devices passed in the machine or one which may be arranged to operate only on certain of the printing devices sequentially passing through the machine wherein such printing devices are arranged in groups embodying lead and follower printing devices. Moreover, the selector is so arranged that an operation opposite to that for which it is set may be readily brought about by merely varying the length of one of the detecting members.

In the foregoing description I have set forth a selected embodiment of my invention, but it is to be understood that this is capable of variation and modification and I therefore do not wish to be limited to the precise details set forth but desire to avail myself of such changes and modifications as fall within the purview of the following claims.

I claim:

1. In a printing machine, printing means,

- means for sequentially moving lead and follower printing devices past the printing means, a selector for determining the operation of said printing means, and detecting means including a part cooperating with the lead printing devices to determine the set-up of said selector and another part cooperating with the follower printing devices to maintain the set-up of said selector.
2. In a printing machine, printing means, means for sequentially moving lead and follower printing devices past the printing means, a selector for determining operation of the printing means from the lead printing devices, and means for preventing operation of the selector on follower printing devices.
3. In a printing machine, printing means, means for sequentially moving lead and follower printing devices past the printing means, a selector for determining the operation of the printing means from the lead printing devices, and electrically operated means for preventing operation of the selector on follower printing devices.
4. In a printing machine, printing means, means sequentially moving lead and follower printing devices past the printing means, a selector for determining the operation of the printing means from the lead printing devices, means for preventing operation of the selector on follower printing devices, and means cooperating with identifying means on the printing devices for controlling the operation of the means preventing selector operation.
5. In a printing machine, printing means, means for sequentially moving lead and follower printing devices past the printing means, a selector for determining the operation of the printing means from the lead printing devices, electrically operated means for preventing operation of the selector on follower printing devices, and means cooperating with identifying means on the printing devices for controlling the operation of said electrically operated means.
6. In a printing machine, printing means, means sequentially moving lead and follower printing devices past the printing means, a selector for determining the operation of the printing means from the lead printing devices, means for preventing operation of the selector on follower printing devices, and means operated at a predetermined time in the operation of the machine for controlling the operation of the means preventing selector operation.
7. In a printing machine, printing means, means for sequentially moving lead and follower printing devices past the printing means, a selector for determining the operation of the printing means from the lead printing devices, electrically operated means for preventing operation of the selector on follower printing devices, and means operated at a predetermined time in the operation of the machine for controlling the operation of the electrically operated means.
8. In a printing machine, printing means, means sequentially moving lead and follower printing devices past the printing means, a selector for determining the operation of the printing means from the lead printing devices, electrically operated means for preventing operation of the selector on follower printing devices, means cooperating with identifying means on the printing devices for controlling the operation of said electrically operated means, and means operated at a predetermined time in the operation of the machine for regulating the operation of
- the means operated by the identifying means on the printing devices.
9. In a printing machine, printing means, means for sequentially moving lead and follower printing devices through selecting and printing positions in the machine, a selector operable on said printing devices when in selecting position for determining operation of said printing means, and means for rendering said selector inoperative when a follower printing device is in selecting position.
10. In a printing machine, printing means, means for sequentially moving lead and follower printing devices through selecting and printing positions in the machine, a selector for determining operation of the printing means and including portions adapted to be set in determined positions when the selector operates on a lead printing device in selecting position, and means for holding said portions in a set position when a follower printing device is in selecting position.
11. In a printing machine, printing means, means sequentially moving lead and follower printing devices through selecting and printing positions in the machine, a selector operable on said printing devices when in selecting position for determining the operation of said printing means, and electrically operated means for holding said selector in the position in which it is set by cooperation with a lead printing device when a follower printing device is in selecting position.
12. In a printing machine, printing means, means sequentially moving lead and follower printing devices through selecting and printing positions in the machine, a selector operable on said printing devices when in selecting position for determining the operation of said printing means, electrically operated means for holding said selector in the position in which it is set by cooperation with a lead printing device when a follower printing device is in selecting position, and means operated at a predetermined time in the operation of the machine for controlling the operation of said electrically operated means.
13. In a printing machine, means sequentially moving printing devices through the machine, printing means for making multiple impressions from a printing device fed into position therebelow, a selector for determining the operation of said printing means, and common means for rendering said selector and said moving means inoperative as said printing means makes multiple impressions from a printing device in printing position.
14. In a printing machine, means sequentially moving lead and follower printing devices through selecting and printing positions in the machine, printing means for making multiple impressions from a printing device fed into printing position therebelow, a selector operable on said printing devices when in selecting position for determining the operation of said printing means, common means for rendering said selector and said moving means inoperative as said printing means makes multiple impressions from a printing device in printing position, and means for holding said selector against operation when follower printing devices are in selecting position, said common means rendering said moving means inoperative without affecting the operation of said holding means.
15. In a printing machine, means sequen-

- tially moving lead and follower printing devices through selecting and printing positions in the machine, printing means, means for operating said printing means, means for rendering said 5 moving means inoperative for a predetermined period whereby more than one impression may be made from a printing device in printing position, a selector for controlling operation of said printing means and operable on said printing 10 devices when in selecting position for determining from a lead printing device whether or not any impressions are to be made from the printing devices when fed into printing position, and means for holding said selector against operation 15 when follower printing devices are in selecting position.
16. In a printing machine, means sequentially moving lead and follower printing devices through selecting and printing positions in the 20 machine, printing means, means for operating said printing means, means for rendering said moving means inoperative for a predetermined period whereby more than one impression may be made from a printing device in printing position, a selector for controlling operation of said printing means and operable on said printing 25 devices when in selecting position and adapted to be latched in a predetermined position as determined by identifying means on the lead 30 printing devices, and means for holding said selector in latched or unlatched condition when follower printing devices are in selecting position.
17. In a printing machine, printing means, means for sequentially moving lead and follower 35 printing devices through printing position in the machine, means for controlling operation of the printing device moving means whereby multiple impressions may be made from a printing device in printing position by said printing means, a selector for determining the operation of said 40 printing means from the lead printing devices, and common means for rendering said selector and said moving means inoperative when said printing means operates to make multiple impressions from a printing device in printing 45 position.
18. In a printing machine, printing means, means for sequentially moving printing devices through printing position in the machine, means 50 for controlling operation of the printing device moving means whereby multiple impressions may be made from a printing device in printing position by said printing means, a selector for determining the operation of said printing means, common means for operating said printing 55 means, printing device moving means, and said selector, and other common means for disconnecting said selector and said moving means from the common operating means when said printing means operates to make multiple impressions from a printing device in printing position.
19. In a printing machine which has means 60 for sequentially moving a plurality of printing devices therethrough, a platen, a continuously driven shaft having means engaged therewith for operating said platen and including means for operating the printing device moving means, a second shaft, and means operated by said 65 second shaft for intermittently suspending the operation of said printing device moving means, the combination therewith of speed-changing means including a plurality of sets of constantly meshed gears of different ratios adapted to operate said second shaft in timed relation with the 70
- first shaft and including means for selectively connecting said gears in driving connection whereby but one of said sets of gears is operable at a given time.
20. In a printing machine, means sequentially moving a plurality of printing devices through the machine, a platen, a continuously driven shaft having means engaged therewith for operating said platen and including means for operating the printing device moving means, a second shaft, a selector for controlling the operation of said platen, and means operated by said second shaft for intermittently suspending the operation of said printing device moving means and said selector. 5
21. In a printing machine, means sequentially moving a plurality of printing devices through the machine, a platen, a continuously driven shaft having means engaged therewith for operating said platen and including means for operating the printing device moving means, a second shaft, a selector for controlling the operation of said platen, means operated by said second shaft for intermittently suspending the operation of said printing device moving means and said selector, and means for operating said second-named shaft in timed relation with the first shaft and including a speed-changing means embodying a plurality of sets of constantly meshed gears of different ratios and means for selectively connecting said gears in driving connection whereby but one of said sets of gears is operable at a given time. 10
22. In a printing machine, printing means, means sequentially moving printing devices through said machine past said printing means, selector means for controlling the operation of said printing means whereby impressions will be made only from determined of the printing devices, and means for reversing the operation of said selector means whereby impressions will be made from printing devices other than those determined by the operation of said selector means before reversing thereof and including a movable member having a notch therein and seating portions adjacent said notch and a member adapted to be seated normally either in said notch or on a seating portion as determined by the position of said movable member. 15
23. In a printing machine including means for sequentially moving printing devices therethrough, printing means, selector means for interrupting operation of said printing means, means on certain of said printing devices for operating said selector means, and means on other of said printing devices for maintaining said selector means in a determined operating position. 20
24. In a printing machine, printing means, means for sequentially moving printing devices through said printing machine past said printing means, a selector for determining operation of said printing means operable from means on said printing devices disposed in certain positions, and means for rendering said selector means inoperative, said last-named means being operable from means positioned on said printing devices other than in said certain positions. 25
25. In a printing machine, printing means including a platen, means for sequentially moving printing devices through said printing machine, a selector for determining the operation of said printing means, means operating in timed relation with said platen for rendering said selector inoperative including a rockable member, and 30

- means connected to said rockable member for manually rendering said selector inoperative.
26. In a printing machine, printing means, means sequentially moving printing devices through the machine, a selector, parts in said selector adapted to be disposed in predetermined positions upon operation of said selector to determine the operation of said printing means, latching means adapted to hold said parts of said selector in said predetermined positions, and means on said printing devices for regulating the operation of said latching means.
27. In a printing machine, printing means, means sequentially moving printing devices through the machine, a selector for controlling the operation of the printing means and including a member having a notch therein and seating portions adjacent said notch and a settable member adapted to be seated normally either in said notch or on a seating portion, and said selector including latching means adapted to hold said selector in positions determined by the location of said settable member relative to the notch or seating portions.
28. In a printing machine, printing means, means sequentially moving printing devices through the machine, a selector for controlling the operation of the printing means and including a movable member having a notch therein and seating portions adjacent said notch and a settable member adapted to be seated normally either in said notch or on a seating portion, said selector including latching means adapted to hold said selector in positions determined by the location of said settable member relative to the notch or seating portions, and means for adjusting the position of said movable member to reverse the operation of said latching means.
29. In a printing machine, operating means, printing means, means for sequentially moving printing devices through said machine, a selector, means for locking said selector in a determined position, means positioned by the locked portions of said selector for disconnecting a portion of said operating means, and means for braking the disconnected portions of said operating means.
30. In a printing machine, operating means, printing means, means for sequentially moving printing devices through said machine, a selector, means for locking said selector in a determined position, means positioned by the locked portions of said selector for disconnecting a portion of said operating means, and electrical means operating in timed relation with said printing means for braking the disconnected portions of said operating means.
31. In a printing machine embodying a platen, a platen operating shaft, and means on said shaft for operating said platen, means sequentially moving printing devices through printing position in the machine and including a rocker, a disc eccentrically mounted on said shaft, means connected to said disc and operable therewith and including a member adapted to receive a reciprocatory movement from said disc upon operation of said shaft, and means connecting said member to said rocker.
32. In a printing machine embodying a platen, a platen operating shaft, means on said shaft for operating said platen, means sequentially moving printing devices through printing position in the machine and including a rocker having a sleeve thereon, operating means on said shaft and including a plunger, and latch means for detachably connecting said plunger to said sleeve to operate said rocker.
33. In a printing machine embodying a platen, a platen operating shaft, means on said shaft for operating said platen, means sequentially moving printing devices through printing position in the machine and including a rocker having a sleeve thereon, a disc eccentrically mounted on said shaft, an operating member carried by said disc and including a plunger extended into said sleeve, and latch means on said rocker and engageable with said plunger to detachably connect said operating member to said rocker.
34. In a printing machine embodying a platen, a platen operating shaft, means on said shaft for operating said platen, means sequentially moving printing devices through printing position in the machine and including a rocker, a disc eccentrically mounted on said shaft, a plunger connected to said disc and adapted to be reciprocated in the movement of said disc with said shaft, a sleeve on said rocker, and latch means for detachably connecting said sleeve to said plunger to operate said rocker with said disc.
35. In a printing machine embodying a platen, a platen operating shaft, means on said shaft for operating said platen, means sequentially moving printing devices through printing position in the machine and including a rocker, a disc eccentrically mounted on said shaft, a plunger connected to said disc and adapted to be reciprocated in the movement of said disc with said shaft, a sleeve on said rocker, and latch means for detachably connecting said sleeve to said plunger to operate said rocker with said disc, another shaft operating in timed relation with said operating shaft, and means on said last-named shaft for controlling said latch whereby said plunger may be disconnected from said sleeve to interrupt movement of said rocker with said disc.
36. In a printing machine, printing means, means sequentially moving printing devices through said machine, a selector including means engageable with members on certain of said printing devices and adapted to move portions of said selector into certain positions for determining the operation of said printing means, and electrical means operable from members on other of said printing devices for holding said selector in said certain positions.
37. In a printing machine through which lead and follower printing devices are fed, an operative means, a selector for determining the operation of said operative means, and detecting means including a part cooperating with the lead printing devices to determine the set-up of said selector and another part cooperating with the follower printing devices to maintain the set-up of said selector.
38. In a printing machine through which lead and follower printing devices are fed, an operative means, a selector for determining the operation of said operative means from the lead printing devices, and means for preventing operation of said selector on follower printing devices.
39. In a printing machine having a selecting position through which lead and follower printing devices are fed, an operative means, a selector operable on said printing devices when in selecting position for determining the operation of said operative means, and means for rendering said selector inoperative when a follower printing device is in selecting position.
40. In a printing machine having a selecting position through which lead and follower print-

ing devices are fed, an operative means, a selector for determining the operation of said operative means and including portions adapted to be set in determined positions when the selector operates on a lead printing device in selecting position, and means for holding said portions in said position when a follower printing device is in selecting position.

41. The combination with a printing mechanism adapted to cooperate successively with each printing device of a group of printing devices having a selected part of a record thereon and in which group there is a lead printing device or a lead and follower printing devices, of means feeding the groups of printing devices through the printing machine, means controlled from the lead printing device of the group for temporarily disabling the printing mechanism without interrupting continued operation of the feeding means, and means for holding said disabling means against operation on the follower printing device or devices of the group.

42. The combination with a printing mechanism adapted to cooperate successively with each printing device of a group of printing devices having a selected part of a record thereon and in which group there is a lead printing device or a lead and follower printing devices, of means feeding the groups of printing devices through the printing machine, a selector for temporarily disabling the printing mechanism without interrupting continued operation of the feeding means, and detecting means including a part cooperating with the lead printing device to determine the set-up of said selector and another part cooperating with the follower printing device or devices to maintain the set-up of said selector.

43. The combination with a printing mechanism adapted to cooperate successively with each printing device of a group of printing devices having a selected part of a record thereon and in which group there is a lead printing device or a lead and follower printing devices, of means feeding the groups of printing devices through the machine and a selecting position therein, a selector operable on said printing devices when in selecting position for temporarily disabling the printing mechanism without interrupting continued operation of the feeding means, and

means for rendering said selector inoperative when a follower printing device is in selecting position.

44. The combination with a printing mechanism adapted to cooperate successively with each printing device of a group of printing devices having a selected part of a record thereon and in which group there is a lead printing device or a lead and follower printing devices, of means feeding the groups of printing devices through the machine and a selecting position therein, a selector for temporarily disabling the printing means without interrupting continued operation of the feeding means and including portions adapted to be set in determined positions when the selector operates on a lead printing device in selecting position, and means for holding said portions in said position when a follower printing device is in selecting position.

45. In a printing machine, printing means, means sequentially moving printing devices through the machine, a selector embodying a member having a notch therein and a shoulder adjacent said notch, settable means adapted to cooperate with said notch and shoulder and normally disposed in a determined position relative to said notch and shoulder, a detaching portion adapted to cooperate with members on said printing devices to automatically determine the relation between said settable means and said notch and shoulder, and means controlled by the relative position of said settable means and said notch and shoulder for determining the operation of said printing means.

46. In a printing machine, printing means, means sequentially moving printing devices through the machine, a selector embodying a member having a notch therein and a shoulder adjacent said notch, settable means adapted to cooperate with said notch and shoulder, manually operable means for positioning said settable means relative to said notch and shoulder, and automatic means cooperating with the printing devices for determining the relation between said settable means and said notch and shoulder, and means controlled by the relative position of said settable means and said notch and shoulder for determining the operation of said printing means.
